Primary Examiner — John Windmuller*Assistant Examiner* — John R Yeh(74) *Attorney, Agent, or Firm* — Nixon Peabody LLP(57) **CLAIM**

The ornamental design for bottle, as shown and described.

DESCRIPTION

FIG. 1 is a perspective view of a bottle.

FIG. 2 is a first side view of the bottle.

FIG. 3 is a second side view of the bottle, which is opposite to the first side view of FIG. 2.

FIG. 4 is a third side view of the bottle, which is adjacent to the first side view of FIG. 2.

FIG. 5 is a fourth side view of the bottle, which is opposite to the third side view of FIG. 4.

FIG. 6 is a top plan view of the bottle; and,

FIG. 7 is a bottom plan view of the bottle.

The portions of the drawings shown in broken lines represent environmental structure and form no part of the claimed design.

1 Claim, 4 Drawing Sheets(56)
